United States Patent Office

Des. 193,001
Patented June 12, 1962

193,001

SEATING UNIT

Ernest Gilbert Mason, Calabasas, Calif.
(3210 Winona Ave., Burbank, Calif.)

Filed Aug. 18, 1961, Ser. No. 66,401

Term of patent 14 years

(Cl. D15—8)

fig. 3

fig. 2

fig. 4

FIG. 1 is a front elevational view of a seating unit embodying my design;

FIG. 2 is a side elevational view;

FIG. 3 is a rear elevational view with portions of the unit broken away for convenience of illustration; and

FIG. 4 is a top plan view thereof.

The dominant features of my design reside in those portions shown in full lines on the drawing

I claim:

The ornamental design for a seating unit, substantially as shown and described.
